(57) **CLAIM**

The ornamental design for a lid for drinking vessel, as shown and described.

DESCRIPTION

FIG. 1 is a plan view of a lid for drinking vessel, showing my new design;

FIG. 2 is a perspective view thereof;

FIG. 3 is another perspective view thereof;

FIG. 4 is a side elevation view thereof, all other sides being a mirror image thereof;

FIG. 5 is a bottom plan view thereof; and,

FIG. 6 is a bottom perspective view thereof.
